The ornamental design for a robotically assisted power line aerial diverter mounting tool, as shown and described.

DESCRIPTION

FIG. 1 is a top perspective view of a robotically assisted power line aerial diverter mounting tool showing my new design;

FIG. 2 is a bottom perspective view thereof;

FIG. 3 is a front elevation view thereof;

FIG. 4 is a back elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines in the drawings illustrate portions of the robotically assisted power line aerial diverter mounting tool and form no part of the claimed design.
